(57) **CLAIM**

The ornamental design for separated finger pad for a surgical suction instrument, as shown and described.

DESCRIPTION

FIG. 1 is a plan view of separated finger pad for a surgical suction instrument.

FIG. 2 is a first side view of the separated finger pad for a surgical suction instrument shown in FIG. 1.

FIG. 3 is a front view of the separated finger pad for a surgical suction instrument shown in FIG. 1.

FIG. 4 is a bottom view of the separated finger pad for a surgical suction instrument shown in FIG. 1.

FIG. 5 is a rear view of the separated finger pad for a surgical suction instrument shown in FIG. 1.

FIG. 6 is a second side view of the separated finger pad for a surgical suction instrument shown in FIG. 1.

FIG. 7 is a first top perspective view of the separated finger pad for a surgical suction instrument shown in FIG. 1.

FIG. 8 is a second top perspective view of the separated finger pad for a surgical suction instrument shown in FIG. 1.

FIG. 9 is a third top perspective view of the separated finger pad for a surgical suction instrument shown in FIG. 1.

FIG. 10 is a fourth top perspective view of the separated finger pad for a surgical suction instrument shown in FIG. 1.

FIG. 11 is a first bottom perspective view of the separated finger pad for a surgical suction instrument shown in FIG. 1.

FIG. 12 is a second bottom perspective view of the separated finger pad for a surgical suction instrument shown in FIG. 1.

FIG. 13 is a third bottom perspective view of the separated finger pad for a surgical suction instrument shown in FIG. 1; and,

FIG. 14 is a fourth bottom perspective view of the separated finger pad for a surgical suction instrument shown in FIG. 1. The broken line showing of parts of the drawings is included for the purpose of illustrating portions of a surgical suction instrument and forms no part of the claimed design.

1 Claim, 14 Drawing Sheets
